UNITED STATES PATENT OFFICE.

JAMES MACPHAIL, OF MOLINE, ILLINOIS, ASSIGNOR, BY MESNE ASSIGNMENTS, TO KILLING MOLDING MACHINE COMPANY, OF DAVENPORT, IOWA, A CORPORATION.

MOLD-FORMING MACHINE.

No. 850,768.

Specification of Letters Patent.

Patented April 16, 1907.

Application filed November 27, 1905. Serial No. 289,295.

To all whom it may concern:

Be it known that I, JAMES MACPHAIL, a citizen of the United States of America, residing at Moline, Rock Island county, State of Illinois, have invented a new and useful Mold-Forming Machine, of which the following is a specification.

My invention relates to improvements in machines for forming sand molds for casting metals; and it has for its object the quickening of the operation of forming such molds, particularly such molds that the pattern must be withdrawn in a direction at right angles to the plane of the pattern or pattern-plate, and the construction of a simple, easily-operated, and inexpensive machine for that purpose. I attain these objects by the mechanism illustrated in the accompanying drawings, in which—

20 Figure 1 is a side view of the machine, showing the pattern drawn from the mold and held by detents or stops, and in dotted lines the swinging frame in position to have the flask placed upon it to form a new mold. 25 Fig. 2 is a top view of the machine in the same position as in Fig. 1. Fig. 3 is a vertical section through the machine on the line X X of Fig. 2 and shows the mold formed in the flask.

30 The frame is in two parts, a base-frame A and a swinging frame or rocking frame B. The base-frame A comprises two lateral parts or bars connected by a rib A⁵ and suspended U-shaped braces A³, the latter being supported between the lateral parts A and secured by bolts A⁴ and forming a rest for the bottom board when flask is inverted.

35 Each lateral part is provided with a raised middle bearing A', through which passes the pivot or shaft C', and also with a raised support A² at one end, upon which an arbor g of the pattern-plate D rests when the pattern-plate is in its first position.

40 For convenience of reference I designate the position of the swinging or rocking frame, pattern-plate, pattern, and flask when the flask is ready to be filled with sand and rammed as the "first" position, and the position when the pattern has been drawn from the mold as the "second" position.

45 The swinging frame B is secured to the pivot or shaft C', which passes through it, by set-screws d'. The free end is provided with

a handle B' to enable the operator to grasp and swing the frame readily. A stripping-plate D' is secured to the frame B, and a pattern-plate D is slidably mounted upon guides E', secured to the swinging frame. The pattern D² is secured to or formed integral with the pattern-plate D, which is provided with rollers G G, mounted upon arbors g g.

50 Adjustable detents or stops H H, each consisting of a lever with a long and two short arms, are pivoted upon each end of the shaft C'. Lugs a' are formed upon each side of the frame, through which pass set-screws a² a², adapted to adjust the position of the stops H H and limit the descent of the long arms H' H'. Each short arm H² is provided with an attached set-screw I', to which one end of a spring I is secured, the other end of the spring I being secured by a hook K', formed upon a bolt adjustably secured in the lug K by a nut K².

55 One end of the shaft C' is formed into a crank C², which engages a compression-spring C³ by suitable rods or links, the opposite end of the spring C³ being secured to the base-frame by a suitable rod or link.

60 The stripping-plate D' is of sufficient thickness to assist in guiding the pattern when withdrawn and may be made of sufficient thickness to obviate the need of the guides E' E'. The guides E' E' are fitted with pins or keys e e, so as to limit the movement of the pattern-plate thereon.

65 A removable clamp is formed by the bent or curved bar C, one end of which is formed into an arm having a handle C⁴, adapted to be grasped by the hand of the operator with the handle B'. The other end is formed with an arm having a bent extremity adapted to rest against the pivot or shaft C'. The middle portion of the clamp C is recurved to press against the bottom board F' and to hold the bottom board F' and the flask F in position during the partial revolution of the swinging frame.

70 In making molds by swinging or rocking machines heretofore used it has been impossible to form molds of any depth except from patterns which conformed to the line of travel of the pattern when being withdrawn from the mold without breaking or injuring the mold. The construction shown will allow the formation of molds rapidly and easily

which could not be successfully made by any form of such machines heretofore used. It will also avoid the necessity of gagers and the consequent difficulty in ramming and 5 the amount of lead heretofore required.

The automatic reseating of the pattern-plate when the swinging frame is replaced in its first position increases the speed of the work. The stop H and spring I cushions the 10 descent of the swinging frame into its second position, and the spring I draws the arm H' into a nearly-vertical position when the swinging frame is swung back into the first position, thus leaving the way clear for the removal of the completed mold and flask. 15 The particular form of clamp used has advantages over others now in use, being easily detachable, giving a broad holding-surface, and being easily changed in dimensions for 20 different flasks.

The drawings illustrate the machine with a hub-pattern on the pattern-plate, but obviously the form of the swinging frame, pattern-plate, and stripping-plate may be 25 changed to meet the requirements of each particular case.

In operation the swinging frame B is thrown into the first position. The supports A² A² force the pattern-plate D into position 30 with the pattern D² projecting through the stripping-plate D'. Parting-sand then is sifted or sprinkled on the stripping-plate D' and the flask F placed upon the stripping-plate. The molding-sand is then properly 35 rammed, the bottom board put on, and the clamp C placed with handle adjacent to the handle B' and the opposite end under the shaft C' and its middle portion against the bottom board F' and securely held while the 40 swinging frame is swung or rocked over into the second position. While descending into the second position, the rollers G G, mounted upon the arbors g g, strike the stops H' H', which limit the descent of the pattern. The 45 swinging frame and flask continue their descent until the bottom board rests upon the braces A³ A³, when the pattern is entirely drawn from the mold. The swinging frame is then returned to its first position. The 50 springs I I draw the arms H' H' into an upright position, and the mold and flask can be removed freely.

Various forms of clamp may be used, but the form shown is preferred.

Having shown and described my invention, what I claim, and desire to secure by Letters Patent, is—

1. In a mold-forming machine, the combination of a base, a swinging flask-receiving frame pivoted to said base, a movable pattern member arranged to operate in said frame, and a spring-controlled stop for restricting the movement of said pattern member, substantially as set forth.

2. In a mold-forming machine, the combi-

nation of a base, a swinging flask-receiving frame pivoted to said base, a movable pattern member arranged to operate in said frame, a movable stop for restricting the movement of said pattern member, and adjustable means whereby said stop is restricted in its movement, substantially as set forth. 70

3. In a mold-forming machine, the combination of a base, a swinging flask-receiving frame pivoted to said base, a movable pattern member arranged to operate in said frame, a spring-controlled stop for restricting the movement of said pattern member, and adjustable means whereby said stop is restricted in its movement, substantially as set forth. 75

4. In a mold-forming machine, the combination of a base, a swinging flask-receiving frame pivoted to said base, a movable pattern member arranged to operate in said frame, and a vibratory stop for restricting the movement of said pattern member, substantially as set forth. 80

5. In a mold-forming machine, the combination of a base, a swinging flask-receiving frame pivoted to said base, a movable pattern member arranged to operate in said frame, and a vibratory spring-controlled stop for restricting the movement of said pattern member, substantially as set forth. 85

6. In a mold-forming machine, the combination of a base, a swinging flask-receiving frame pivoted to said base, a movable pattern member arranged to operate in said frame, a vibratory stop for restricting the movement of said pattern member, and adjustable means whereby said stop is restricted in its movement, substantially as set forth. 90

7. In a mold-forming machine, the combination of a base, a swinging flask-receiving frame pivoted to said base, a movable pattern member arranged to operate in said frame, a vibratory spring-controlled stop for restricting the movement of said pattern member, and adjustable means whereby said stop is restricted in its movement, substantially as set forth. 95

8. In a mold-forming machine, the combination of a base, a swinging flask-receiving frame pivoted to said base, a pattern member arranged to operate in said frame, arbors carried by said pattern member, and movable stops arranged to be engaged by said arbors, substantially as set forth. 100

9. In a mold-forming machine, the combination of a base, a swinging flask-receiving frame pivoted to said base, a pattern member arranged to operate in said frame, arbors carried by said pattern member, and movable spring-controlled stops arranged to be engaged by said arbors, substantially as set forth. 105

10. The stop mechanism for arresting, low- 110

ering, and withdrawing a pattern-plate, consisting of a lever having a long arm, against which the pattern-plate impinges, and two short arms, a spring connected with one short arm so as to seat the long arm, and means against which the other short arm is adapted to impinge so as to limit the movement of the long arm.

11. The stop mechanism for arresting, lowering, and withdrawing a pattern-plate, consisting of a lever having a long arm, against which the pattern-plate impinges, and two short arms, a spring connected with one short arm so as to seat the long arm, means for adjusting the tension of the spring and means against which the other short arm is adapted to impinge so as to limit the movement of the long arm.

12. The stop mechanism for arresting, lowering, and withdrawing a pattern-plate consisting of a lever having a long arm, against which the pattern-plate impinges, and two short arms, a spring connected with one short arm so as to seat the long arm, a lug, an eye-screw connected with the spring and adjustable in the lug for adjusting the tension of the spring, and means against which the other short arm is adapted to impinge to limit the movement of the long arm.

13. The stop mechanism for arresting, lowering and withdrawing a pattern-plate consisting of a lever having a long arm, against which the pattern-plate impinges, and two short arms, a spring connected with one short arm so as to seat the long arm, a lug, and a set-screw working in the lug against which the other short arm is adapted to impinge so as to limit the movement of the long arm.

14. A mold-forming machine comprising a base-frame, a swinging frame, a pattern-plate, and a stop pivoted to the base-frame, and consisting of a long arm, two short arms, a spring connected with one short arm, and means located upon the base-frame against which the other short arm is adapted to impinge for limiting the movement of the long arm.

15. A mold-forming machine comprising a base-frame, a swinging frame, a pattern-plate, and a stop pivoted to the base-frame, and consisting of a long arm, against which the pattern-plate impinges, two short arms, a spring connected with one short arm so as to seat the long arm, means located upon the base-frame for adjusting the tension of the spring, and means located upon the base-frame against which the other short arm is adapted to impinge so as to limit the movement of the long arm.

16. A mold-forming machine comprising a base-frame, a swinging frame, a pattern-plate, and a stop pivoted to the base-frame and consisting of a long arm against which the pattern-plate impinges, two short arms, a spring connected with one short arm so as to seat the long arm, a lug located upon the base-frame, an eye-screw connected with the spring and adjustable in the lug for adjusting the tension of the spring, and means against which the other short arm is adapted to impinge to limit the movement of the long arm.

17. A mold-forming machine comprising a base-frame, a swinging frame, a pattern-plate, and a stop pivoted to the base-frame consisting of a long arm, against which the pattern-plate impinges, two short arms, a spring connected with one short arm so as to seat the long arm, a lug located upon the base-frame and a set-screw working in the lug against which the other short arm is adapted to impinge so as to limit the movement of the long arm.

18. In a mold-forming machine, the combination with a base, of a swinging frame pivoted therein adapted to receive a flask, guides secured to the swinging frame, a pattern-plate slidably mounted upon the guides, a stripping-plate secured to the swinging frame, and arbors secured to the pattern-plate, and stops secured to the base-frame to engage the arbors.

19. In a mold-forming machine, the combination with a base-frame of a swinging frame pivoted therein adapted to receive a flask, guides secured to the pivoted frame substantially at right angles thereto, a pattern-plate slidably mounted upon the guides and arbors secured to the pattern-plate adapted to be engaged by spring-stops adjustably secured to the base-frame.

20. In a mold-forming machine, the combination with a base-frame, of a swinging frame pivoted therein with a stripping-plate secured on the swinging frame adapted to receive a flask, a pattern slidably mounted in the stripping-plate upon a pattern-plate, trunnions secured to the pattern-plate adapted to be engaged by adjustable spring-stops secured to the base-frame.

In testimony whereof I have signed my name to this specification in the presence of two subscribing witnesses.
